UNITED STATES PATENT OFFICE

2,604,913

MACHINE FOR SLICING VENEER STRIPS
FROM WOOD BLOCKS

Charles F. Bamford, Portland, Oreg.

Application March 25, 1947, Serial No. 737,044

6 Claims. (Cl. 144—162)

1

My invention relates to machines for slicing veneer strips from wood blocks, and has for its general object the development of a wood slicer in which the parts may be accurately adjusted quickly and efficiently to produce a superior operation and a superior product.

A further object of my invention is to provide a wood slicing machine of this character in which provision is made to hold blocks of wood to be sliced, which blocks may vary substantially in size and which blocks of wood may be irregular.

A further and more specific object of my invention is to provide a slicer of this character in which the cutter assembly is held to a closely defined path but the parts are so arranged that they accommodate expansion and contraction, irregularities in the block of wood being operated upon, and the operating parts are so arranged as to withstand shock resulting from severe operation.

A further and more specific object of my invention concerns the provision of adjusting devices by which the fixed cut-off bar may be adjusted with respect to the stroke of the cutting head assembly. Heretofore, said adjustment was made by adjusting the operating length or limits of the stroke of the cutting head assembly. I have discovered that the stroke of the cutting head assembly may be left unaffected and a simple, efficient and speedy adjustment may be provided for the cut-off plate to make said relative adjustments.

A further and more specific object of my invention is to provide a hydraulically actuated control for the hold-down bar which holds a block of wood being sliced upon the cut-off bar. Sufficient pressure must be maintained upon said block to hold the latter upon the cut-off bar, but yet this should not be so severe that it prevents the feeding mechanism from moving the block of wood being sliced progressively toward the slicer knife in making the successive cuts. It is essential, also, that there be some accommodation in the mounting for the hold-down bar so that if there are irregularities in the block surface, said hold-down bar may accommodate itself to such irregularities. That is, the bar accommodates itself to the block if the upper face of said block is not plane and level.

Further and other details of my invention and the advantages thereof are hereinafter described with reference to the accompanying drawings, in which:

Fig. 1 is a plan view of a slicer embodying my invention with portions shown broken away to disclose details of construction thereof;

2

Fig. 2 is an end elevation thereof taken in the direction of the arrow 2 in Fig. 1;

Fig. 3 is a longitudinal section through said machine taken on the line 3—3 in Fig. 1;

Fig. 4 is a transverse section taken on the offset section line 4—4 in Fig. 3;

Fig. 5 is a sectional view taken on the line 5—5 in Fig. 1;

Fig. 6 is a detail view, partially in section, taken on the line 6—6 in Fig. 1;

Fig. 7 is a more or less diagrammatic view, partially in section, taken on the line 7—7 in Fig. 1;

Fig. 8 is an enlarged sectional view through the cutting head, cut-off bar and hold-down bar, and shows means for varying the position of the cut-off bar with respect to the cutting assembly; and

Fig. 9 is a detail view, taken substantially on the line 9—9 of Fig. 1 but rotated about 30° to show the squared aperture in which the end of one guide bar is mounted so lateral adjustment automatically will be made under working stress.

A slicer embodying my invention is supported by a box like frame comprising two transverse vertical end members 1a—1b, a lower longitudinal member 1c, and an upper longitudinal member 1d.

Said frame defines a working space 2, in which a driving motor 3, illustrated as an electric motor, is mounted and drives a pulley 4 from motor pulley 5 through a plurality of V-belts 6. See Figs. 3 and 1.

The pulley 4 preferably is made quite massive so that it operates on the principle of a flywheel, a section therethrough being illustrated in Fig. 6. Said pulley 4 is keyed to a shaft 7, having appropriate bearings in the frame member 1a. Also keyed to said shaft is a driving pinion 8.

Said driving pinion 8 meshes with and drives a pair of gears 9, which gears 9 are supported by crank discs 11 and 12, respectively. Shafts 9a extend through crank discs 11 and 12, respectively, and support said discs. I preferably make said gears 9 separable so they may be easily replaced. Said gears and the crank discs to which they are secured, and with which they become a single operating unit, are housed within the frame in the manner shown in Fig. 5 and are enclosed by shields 13—13a, respectively, to keep out dirt, dust, and other foreign matter. Said shields are fitted quite tightly so the spaces 14 within the frame and behind said shields may constitute oil reservoirs to lubricate said gears, discs, and the bearings therefor. As is shown in Fig. 5, each crank disc extends through a central aperture

55

in the shield with which it has a wiping contact. Eccentrically from the axis of the shaft upon which each of said crank discs is mounted are crank pins 11a-12a, respectively.

The cutting knife for performing the slicing operation is an operating part of cutting head assembly 15, which extends across the central portion of the end of the machine in the manner illustrated in Fig. 2. It comprises a sash 16, which terminates in terminal sleeves 16a-16b, respectively. Said sleeves are slidably mounted upon obliquely disposed guide bars 17-17a, respectively, held by clamps 18-18a to the frame of the machine. Inasmuch as said guide bars have to be strong and true, and the cutting assembly must follow a fixed path, it is desirable that one of said guide bars be adjustable. To this end, I make the clamps 18 for accommodating the guide bar 17 with some adjustment laterally. This is illustrated in the upper left-hand portion of Fig. 1 and, more particularly, in the detail view of Fig. 9. That is to say, a squared aperture 18b is arranged in said clamp, and the upper end 17b of the guide bar 17 is narrower than the aperture 18b but is the same thickness as the depth of said aperture. The clamping plate 19 spans said aperture and slidably holds the bar in place, but permits it to adjust itself automatically under stress to maintain true and free operation of the cutting-head assembly. This is necessary not only to accommodate any slight mechanical deviations, but also is necessary to accommodate longitudinal expansion of the cutting head assembly. The guide bar 17 is held against longitudinal movement and movement which would shift the axis toward and from the frame, but does permit it to move freely in a plane parallel to the face of the frame to accommodate these changes in operating conditions.

A pair of connecting rods 20-21 join the crank discs 11 and 12, respectively, to said cutting head assembly, and as the crank discs rotate, said connecting rods move the cutting head assembly obliquely along a path defined by said guide bars 17-17a.

One of the important features of novelty of my invention is next described. Inasmuch as the position of the cutting edge 31a of the knife 31 varies with wear and adjustment, it has been deemed necessary heretofore to accommodate this change in position by varying the length of the connecting rods 20-21. This provides a complicated and insecure structure, and the making of the adjustment is difficult because of the close working tolerances that must be maintained. I accomplish this result in the following manner: I make the cut-off bar 25 and its support 22 as a separate unit and make it adjustable on the frame. Referring to Fig. 8, the cut-off bar bracket or support 22 is releasably secured to the frame member by a pair of clamping screws 23. These pass through elongated apertures 22a in the cut-off bar support and thus define guide members restraining the bracket 22 to vertical adjustment only. The cut-off bar bracket or support 22 is vertically adjustable by adjusting screws 24 which bear upon the upper surface of the frame member 1b. The cut-off bar 25 is adjustably mounted on the top of the cut-off bar bracket or support 22 by clamping screws 26 which pass through apertured holes 25a in the cut-off bar. The cut-off bar may be adjusted horizontally, that is, laterally of its support, by backing screws 27. The said backing

screws 27 are adjusted to fixed position and are then locked in said position by lock nuts 27a thereon.

A block of wood 28 to be sliced is supported on said cut-off bar and slidably held upon the cut-off bar by a hold-down bar 29.

The cutting head assembly is supported by the sash 16. The knife bar 30 is adjustably mounted in the sash by means of adjustably mounted brackets, lugs, adjusting screws, and various devices, so that a very close fit and precise position may be attained. These parts are shown in Figs. 2 and 8, but form no particular part of my invention and thus will not be described in further detail. The knife 31 is obliquely adjustable in the knife bar by means of adjusting screws 32. The knife is held in position by a clamp bar 33 held by bolts shown in dotted outline in Fig. 8. The under side of the knife bar is curved and defines the upper portion of a throat 34 through which slices 28a cut off from the block 28 are discharged. Underneath said throat 34 is pressure bar 35, held down by clamp 36, and adjusted by screw 37. The clamp bar 36 is held by screws 38.

All of the foregoing, with regard to the knife and its supports, is generally old in the art. Suffice it to say that the knife must be adjusted for cutting different types of wood, and the cut-off bar varies in height and, generally, there must be some accommodation of said cutting structures with respect to each other, which requires that an adjustment be made between the knife edge 31a and the cut-off bar 25. This may be accomplished, as I have described previously, by adjusting the cut-off bar 25 vertically and leaving the path of travel of the knife unvaried. This may be done more precisely, more expeditiously, and more certainly by the structures illustrated herein and previously described than by varying the length of the connecting rods, which is the old practice.

Next, referring to the hold-down feature of my invention: A slicer of this character must accommodate itself to blocks of different thickness and to different types of wood. Said blocks frequently are irregular and uneven. There must be some accommodation in the hold-down bar 29, and the hold-down bar assembly must be capable of quick actuation and accommodation to the surface upon which it bears. I accomplish this by devices shown most clearly in Figs. 6, 7 and 8. The hold-down bar 29 is carried by a hold-down bar bracket 39, the point of joinder being made through adjusting screws 40, which permits the toe of the hold-down bar to be moved toward and from the path of travel of the knife.

The hold-down bar bracket 39 spans the cutting assembly, and is secured to spring barrels 41 and 42 in the manner shown in Fig. 4. The ends of said bracket may selectively be joined to any of a number of holes 41a-42a in ears 41b-42b, in the spring barrels 41-42, respectively. Operating cylinders 43 and 44 underlie the spring barrels 41 and 42, respectively, and have pistons 43a-44a, respectively, therein. Said pistons 43a-44a, respectively, have rods 45 and 46 extending upwardly therefrom and they extend centrally through barrels 41-42, respectively. Said rods each have springs 47-48, respectively, surrounding them, which springs are housed within the barrels 41-42, respectively. The upper end of each of the springs bears 75 against a sleeve 49, which is secured to the rods

and slidably engages the upper end of a spring barrel. Spring barrels 41—42 are held against movement downwardly upon the respective rods 45 and 46 by a set collar 50 secured to each of said rods. Then, when the hold-down bar rides over a slightly higher surface, the bar and its bracket may lift the spring barrel due to the compressibility of the spring therein. The springs are set under initial tension, the lower end of each of the spring barrels bearing against the stop collar which underlies it. In operation, I normally further compress said springs so as to space the end of each of the barrels a quarter inch or so from the stop collar, so that the ends of the hold-down bar brackets are floating above the stop collar and the hold-down bar is subject to the pressure of the springs thereon. If the lower ends of each of the spring barrels were set initially to rest upon the set collars and the hold-down bar moved across a low spot, the set collars would prevent the hold-down bar from keeping in contact with the block being sliced, under said circumstances.

The upper ends of each of said rods 45—46 are formed into rack bars 45a—46a, having rack teeth upon one face thereof. A transverse shaft 51 spans said rods and carries pinions 51a—51b at the ends thereof, which pinions mesh with the rack bars and transmit the movement of one directly to the other. This keeps the two ends of the hold-down bar in fixed relation and requires said hold-down bar to move in parallel planes, except as said ends are permitted to move relatively, due to the yielding pressure exerted by the springs in the spring barrels.

I preferably utilize an hydraulic fluid in connection with the operating cylinders 43—44, and the cylinders are double acting; that is, operating fluid is introduced and withdrawn from both sides of the pistons 43a—44a, respectively, in said operating cylinders. The springs thus provide that measure of accommodation to permit the hold-down bar to accommodate itself to an irregular or uneven upper surface of the block being sliced.

In Fig. 7, I illustrate the manner in which fluid is introduced to said two cylinders, which are diagrammatically shown detached from the structure of the slicer for the purpose of illustration. Conduits 52—52a provide a control for fluid flowing to and from operating cylinder 43, while conduits 53—53a perform a similar function for the operating cylinder 44. A common control and distributing valve 54 diverts the flow of fluid into either of said two systems of conduits. Said control and distributing valve 54 performs another very useful and important function, namely; that it may be capable of cutting flow off from both conduits and to lock the operating cylinders 43—44 and the pistons therein at a fixed position.

Operating fluid under pressure may be supplied to said valve 54 from any convenient source. In Fig. 7, I illustrate two pipes, an intake pipe 54a and a discharge pipe 54b.

Other operating devices are actuated by hydraulic fluid and thus said pipes may connect with a common reservoir or a common pressure supply system. This is not necessary but is desirable to effect good design. I thus have indicated in Fig. 3 that said pipes lead to a reservoir 55 and stub ends of pipes 55a and 55b may join with said pipes 54a—54b to complete an operating circuit. Pressure is maintained in the pressure line from said reservoir by a pump 56, powered by 75

a motor or other power plant, indicated in Fig. 3 in dotted outline as 57.

Blocks of wood 28 to be fed under the hold-down bar and to be subject to slicing by the cutting head assembly are fed by a hydraulically actuated knee 58, which is shown most clearly in Fig. 3. Said knee is carried by a piston rod 59, which, in turn, is actuated by an operating cylinder 60, controlled by a main control valve 61. Said cylinder is operated also by hydraulic fluid, which is supplied through pipes 62—63 from the reservoir 55. A proper operating pressure is maintained in the supply line 62 by a pressure relief valve 64.

15 The ports leading from the main control valve 61 to the ends of the operating cylinder 60 are indicated in dotted outlines. That is to say, the operating cylinder is double acting. Underlying the piston rod 59 is a guide rod 65 and the hydraulically actuated knee 58 has a sleeve 58a which encircles and slides upon said guide rod. I preferably provide a bumper spring 66 between the end of the piston rod and the hydraulically actuated knee so as to eliminate shock, said spring encircling a reduced portion 59a of the piston rod, and the knee is held upon said reduced portion by a nut 67.

20 I preferably provide operating devices which are in part mechanically actuated and in part manually operated. This is a mere matter of choice, but I have illustrated the actuating controls in this manner. Said actuating controls are illustrated in Figs. 1 and 7 most clearly. The connection from the operating handles to the valves is illustrated most clearly in Fig. 3 and reference is also had thereto.

25 A pair of operating handles 68 and 69 are arranged side by side, the operating handle 68 operating the hold-down mechanism, and the operating handle 69 controlling the forward motion of the hydraulically actuated knee. The operating handle 68 is fixed to a rock shaft 70, having an arm 71 also secured thereto, which is joined by a link 72, having a clevis 72a at the end thereof and joined to the operating lever 73 of the control and distributing valve 54. Movement of the operating handle 68 in one direction thus causes the lever 73 to move correspondingly, to cause the hold-down bar to move in one direction. The opposite movement of the operating handle 68 causes a corresponding movement of the valve operating lever 73 in a similar direction to reverse the valve and to actuate the hold-down mechanism in the opposite direction.

30 Surrounding said rock shaft is a sleeve 74, having an arm 74a extending laterally thereof. A control rod 75 leads to and joins with the slidable plunger 61a in the main control valve 61 to actuate it. Mounted upon control rod 75 is a clamp arm 79 which is connected to arm 74a by control link 80.

35 I preferably provide a laterally extending arm 58b on the hydraulically actuated knee to engage a stop on the control rod 75, and thus when the knee moves in closest proximity to the cutting head assembly, it moves said rod 75 and reverses the feed to move the knee toward the right, as it is shown in Fig. 3. As I have said, this is the particular type of control which I have selected for the purpose of illustration. It plays no important part in my present invention, however.

40 Overlying the operating cylinder 60 and its associated mechanism is a horizontally disposed roof 76. This prevents any dirt from passing down into the operating mechanism. Overlying

said roof is a grilled shed 77 comprised of sloped angular bars 77a. I also preferably provide a cover 78 over the hydraulically actuated knee 58 and its piston rod, upon which blocks of wood may rest as they pass from the grilled shed into position, where they may be pushed forward by said knee. Said cover 78 is attached to the knee 58 and slides beneath the roof 76, as is shown in both Figs. 3 and 7.

The operation of a slicer embodying my invention is as follows:

Referring first to Fig. 3: Blocks of wood of lesser length than that of the width of the knife assembly are placed crosswise of the grilled shed 77, and the hydraulically actuated knee 58 is retracted until it passes beneath said shed. A block of wood 28 to be sliced then moves down until the knee engages it, and then it is moved to a position underlying the hold-down bar. The hold-down bar bracket 39 may be lifted substantially above the surface of said block 28, and then the actuating cylinders 43-44 have operating fluid introduced at their upper ends to force the pistons 43a-44a downwardly. The pressure should be sufficient to hold the block firmly on the cut-off bar. The pressure should not be sufficient, however, to prevent said block from being moved laterally across the latter under the action of the hydraulically actuated knee 58. Assuming that the block is positioned at the correct height with relation to the stroke of the cutting head assembly, it may be moved forward until slices 28a are cut from the block, as indicated in Fig. 8. If said cut-off bar is not properly positioned either vertically or laterally, the cut-off bar support may be lifted by the manipulation of adjusting screws 24, and if it is not adjusted laterally to its proper position, this is done by backing off the clamping screws 26 and properly adjusting the backing screws 27 and locking the latter in place by means of lock nuts 27a.

As has been pointed out, the driving motor 3 operates the cutting head assembly through the various belts and pulleys, gears and pinions, and the cutting head assembly moves diagonally across the face of the block until the block is reduced to slices. When the knee approaches the cutting assembly to an arbitrary limit of travel, it actuates the control and distributing valve 61 to cause the knee to be retracted to its original position beneath the grilled shed 77. Any shock between the knee and the block of wood is absorbed by the bumper spring 66, which yields in the presence of a resisting pressure of predetermined value. Likewise, the hold-down bar is resiliently held in position by the springs 41-42 in the spring barrels 41-42. The block is moved forward under the constant pressure of the knee, and when the knife assembly is lifted for the next succeeding stroke, the block moves forwardly to bear against the wearing plate 16c on the face of the sash 16, as is shown in Fig. 8. The degree to which the pressure bar 35 overhangs the face of said wearing plate has been exaggerated somewhat in Fig. 8. It extends beyond the wearing plate only a very small fraction of an inch, and the purpose of said pressure bar is to interpose pressure immediately adjacent the cutting edge 31a of the knife 31 to aid in causing said knife to make a clean, sharp incision to slice off smooth surface slices 28a from the face of the block of wood 28.

I claim:

1. In a veneer slicer having a frame, a cutting knife assembly adapted to traverse a fixed path

across the slicer frame, a cut-off bar mounted upon said frame by means of a bracket movable in a vertical direction only, said cut-off bar being positioned to support a block of wood to be sliced, means for feeding said block of wood over the cut-off bar and transversely of the path of travel of the cutting knife, the combination therewith of an elongate hold-down bar adapted to be held in sliding pressure engagement with the upper surface of said block of wood, a positive pressure applying means joined to each end of said elongate hold-down bar for adjusting and holding said hold-down bar in a selected pressure applying position, and an elastic spring device in each said pressure applying means to permit the hold-down bars individually to yield in the presence of pressure substantially in excess of the selected pressure.

2. In a veneer slicer having a frame member, a cutting head assembly including a cutting knife, means mounting said cutting head assembly upon said frame member for reciprocable movement at an oblique angle across and within a fixed vertical plane, an elongated cut-off bar terminating immediately adjacent said fixed plane and lying in a plane which is perpendicular to said fixed plane, a bifurcated movable bracket straddling a portion of said frame and supporting and detachably secured to said cut-off bar, and an adjustable guide member means interconnecting said movable bracket and frame member and restraining the former to adjustment movement only in a direction parallel said fixed plane whereby the operating relation of said cutting head assembly and said cut-off bar may be adjusted without varying the operating path of said cutting head assembly.

3. In a veneer slicer having a frame member, a cutting head assembly carrying a cutting knife, a pair of spaced guide means mounting said cutting head assembly upon said frame member for reciprocable movement at an oblique angle across and within a fixed vertical plane, said guide means including a guide sleeve operatively encompassing and slidable over a complementary elongated guide rod, one of said guide rods being fixed relative to said frame, the other of said guide rods being supported at one end and having the other end slidably carried within a hollow clamp having an aperture means for restricting the free movement of the said other guide rod end to a lateral direction within said fixed vertical plane and substantially perpendicular to said oblique angle reciprocable movement whereby the guide means for said reciprocable cutting head assembly automatically will be adjusted for true and free movement during operation.

4. In a machine for slicing strips from a wood block, a frame member and a cutting head assembly, a pair of spaced guide means secured to said frame member and carrying said cutting head assembly for reciprocable cutting movement within a fixed vertical plane, each of said spaced guide means including a tubular guide sleeve slidably encompassing a complementary elongated guide rod, one of said elongated guide rods having both ends thereof fixed to said frame, the other of said elongated guide rods having one end supported by said frame and having the other end slidably carried within a hollow clamping means for restricted and limited lateral movement in a plane parallel said fixed vertical plane and in a direction substantially perpendicular the direction of reciprocation of said cutting head assembly, an elongated cut-off bar for support-

ing the wood block as strips are sliced therefrom by said cutting head assembly, a movable bracket means supporting and mounting said cut-off bar in a plane perpendicular to said fixed vertical plane, and an adjustable guide member means interconnecting said moveable bracket and frame member and restraining the former to free movement only in a direction parallel said fixed vertical plane.

5. In a machine for slicing strips of veneer from a wood block, a frame member, a cutting head assembly carrying a cutting knife, means mounting said cutting head assembly upon said frame member for a reciprocable movement at an oblique angle across and within a fixed vertical plane, an elongated cut-off bar for supporting the wood block as strips are sliced therefrom by said cutting knife, said cut-off bar terminating immediately adjacent said fixed vertical plane and being mounted upon said frame member to lie in a plane perpendicular to said fixed vertical plane, means for feeding the wood block over said cut-off bar toward said fixed vertical plane, an elongated hold-down bar having a narrow but elongated contact area, said hold-down bar being mounted upon said frame above said cut-off bar in position slidably to contact the upper surface of the wood block along said narrow contact area, fluid pressure applying means selectively for adjusting and holding said hold-down bar down against said wood block with a preselected pressure allowing said means for feeding to feed the wood block against the force of the hold-down, and elastic means intermediate said fluid pressure applying means and hold-down bar for yielding in the presence of a back pressure on said hold-down bar which back pressure is substantially in excess of the said preselected pressure.

6. In a machine for slicing a wood block, a frame member, a cutting head assembly, means mounting said cutting head assembly upon said frame member for reciprocable movement within a fixed vertical plane, an elongated cut-off bar for supporting the wood block, said cut-off bar terminating immediately adjacent said fixed vertical plane and lying in a plane which is per-

pendicular to said fixed vertical plane, a bifurcated movable bracket straddling a portion of said frame and supporting said cut-off bar, an adjustable guide member means for limiting the movement of said bifurcated bracket to a direction parallel said fixed plane only, means for feeding the wood block over said cut-off bar toward said fixed vertical plane, a hold-down bar mounted upon said frame above said cut-off bar, fluid pressure applying means selectively for adjusting said hold-down bar to a selected pressure applying position relative to said cut-off bar, and elastic means intermediate said fluid pressure applying means and hold-down bar for yielding the position of said hold-down bar in the presence of a back pressure substantially in excess of the said selected pressure.
